(57) **CLAIM**

I claim the ornamental design for a two-fingered snug-fitting glove for smudgeless touchscreen operation, as shown and described.

DESCRIPTION

FIG. 1 is a perspective view of a two-fingered snug-fitting glove for smudgeless touchscreen operation, showing my new design;

FIG. 2 is a rear elevational view, the front elevational view being a mirror image thereof;

FIG. 3 is a right-side elevational view thereof;

FIG. 4 is a left-side elevational view thereof;

FIG. 5 is a top plan view thereof; and,

FIG. 6 is a bottom plan view thereof.

The broken lines showing a hand in FIG. 1 are included for the purpose of illustrating the invention in use, and form no part of the claimed design. The remaining broken lines in the figures represent stitching and are a part of the claim.
